HENRY DUNPHY, OF NEW YORK, N. Y.

Letters Patent No. 70,706, dated November 12, 1867

IMPROVEMENT IN CLOTH-FOLDING MACHINE.

The Schedule referred to in these Letters Patent and making part of the same.

TO ALL WHOM IT MAY CONCERN:

Be it known that I, HENRY DUNPHY, of the city, county, and State of New York, have invented a new and improved Cloth-Plaiting Machine; and I do hereby declare that the following is a full, clear, and exact description thereof, which will enable others skilled in the art to make and use the same, reference being had to the accompanying drawings, forming part of this specification.

This invention relates to certain improvements on a machine for folding shirt-bosoms, plaits, tucks, &c., for which Letters Patent were granted to me on the 27th day of May, 1862.

The object of this invention is to improve the machine described in the aforesaid Letters Patent so as to perfect it in its construction and operation. In the annexed drawings my invention is illustrated—

Figure 1, sheet 1, being a plan or top view, partly in section, of the same.

Figure 2, sheet 1, is a vertical longitudinal sectional view of the same, taken on the plane $x x$, fig. 1.

Figure 3, sheet 2, is a vertical cross-section of the same, taken on the plane $y y$, fig. 2.

Figure 4, sheet 2, is a vertical cross-section of the same, taken on the line $z z$, fig. 2.

Figures 5, 6, and 7, are sectional views of strips of cloth folded in this machine, and will be hereinafter referred to.

Similar letters of reference indicate like parts.

A is a bed-plate, made of wood or any other suitable material, of sufficient strength to support all the other parts of this machine. The holder B is a wooden or other wedge-shaped bar, which is firmly secured to the bed-plate. At each end of the bar B are arranged two upright cheeks, $a a$, between which the folders are held. The blades C and intermediate pieces $b b$ are made and operate as described in the aforesaid Letters Patent. They are adjusted in accordance with the required folds, and are then at once fastened in the required position by inserting them in a sheet-metal or other frame, c, and securing them by a screw, d, as shown in figs. 2 and 3. Each of the two sets of folders thus made is now placed between the cheeks $a a$, at the end of the bar B, and secured there by means of one or more clamps, e, and set-screws f, as shown in figs. 1, 2, and 3. The benefit of this arrangement is that the folders may thus be set as desired, a certain quantity of material folded, and the folders then removed, and a new set for plaiting in a different style inserted in their place. The arrangement of the old folders is not destroyed, as they are held by the screw d in the frame c, and they may be used again when required; while in my old machine the folders were completely deranged as soon as they were removed from the holder B. The clamps e are made so as to press the cheeks a well against the folders. They are then held in place by means of thumb-screws f. The ironer D is hinged to a stationary block, E, so as to fold upwards instead of sideways, as in my aforesaid patent. A great saving of place is thus gained. Either the ironer or the block E, or both, may be made hollow, or otherwise so arranged that steam or hot air may be passed through the same for heating purposes. It will be seen that the ironer (that is, the ironer and the block E together,) and the holder B incline in opposite directions. The arrangement of the folders, though, places the cloth in an inclined position, with which that of the ironer coincides, the latter being consequently made on an incline for the purpose of accommodating itself to the position of the cloth. The ironer is held down upon the block by means of a slotted sliding plate, g, which is secured to the block by a screw, h, as shown in fig. 1. The cloth, after having passed through the folders and ironer, is brought between a pair of rollers, F F, the lower one being mounted in suitable bearings, which are arranged in uprights G, the latter being secured to the plate A. The upper roller F is secured in sliding bearings i i, and is pressed down upon the lower roller by springs k k, the pressure being regulated by screws l l, as shown. A ring, m, of leather or other suitable material is laid and fastened around each of the rollers F F. The length of these rings coincides with the width of the plaits, and is not longer than the same, to prevent the feeding of the cloth in the wrong direction. The pressure of the upper roller is mainly brought upon those parts of the cloth which have been overlapped, thus completely smoothing those parts, and preparing them for the sewing machine.

The whole machine is set in motion by turning a crank or pulley, u, on the lower roller F. The cloth is then wound upon a drum or roller or reel, of any suitable construction. Before passing it through the folders the cloth is brought over and around a detaining and stretching apparatus, which consists of a roller, n, tapering towards the ends, and mounted in a frame, o, and of a board, p, which is also secured in the frame o, as is

shown more particularly in fig. 2. The cloth is brought from a roller or drum under the board *p*, around its rounded front edge and back, and over the roller *n*, as seen. Then it is brought through the folders. The frame *o* is dove-tailed into two blocks, *r*, in which it slides laterally. The blocks *r* slide forward and backward in grooves, *s*, arranged within the bed *A*, or in rails placed thereon.

The object of this apparatus is to keep the cloth well stretched, and, by means of the tapering ends of the roller *n*, also well spread. By means of the lateral adjustment the cloth can always be brought into the proper directions, the adjustment being required by the variable position and arrangement of the folders. By this machine thousands of yards of cloth may be folded for different purposes, the last end of each web being glued or otherwise secured to the first end of the next web. The whole strips of cloth thus folded may be passed through a sewing machine, thereby overcoming the difficulty of stopping the machine for each separate piece or even web. All kinds and styles of folds can be made in this machine. The laps may be apart from each other, as in fig. 5, or they may touch each other, as in fig. 6, or may overlap and cover each other, as in fig. 7.

Having thus described my invention, I claim as new, and desire to secure by Letters Patent—

1. The arrangement for holding the folders in the machine, consisting of the clamps *e*, in combination with the cheeks *a a* of the holders *B*, the whole constructed and operating substantially as described and specified.
2. The rollers *F F*, provided with narrow rings of leather, rubber, or other similar material, in combination with the folding apparatus, substantially as described and specified.
3. The hinged ironer *D*, in combination with the folding apparatus, substantially as described and specified.
4. The laterally and back-and-forward adjusting, retaining, and stretching apparatus, consisting of the roller *n*, bar *p*, and traversing blocks *o* and *r r*, in combination with this folding apparatus, substantially as described and specified.
5. The roller *n*, tapering towards both ends for spreading and stretching the cloth, in combination with the laterally and back-and-forward adjusting mechanism and the folding apparatus, substantially as described and specified.

HENRY DUNPHY.
